US0D1050873S

(12) **United States Design Patent** (10) **Patent No.:** **US D1,050,873 S**
(45) **Date of Patent:** **** Nov. 12, 2024**

(54) **JOINT FORMER CONNECTOR**

(71) Applicant: **Illinois Tool Works Inc.**, Glenview, IL
(US)

(72) Inventor: **Darrell A. Wiatrowski**, Libertyville, IL
(US)

(73) Assignee: **Illinois Tool Works Inc.**, Glenview, IL
(US)

(**) Term: **15 Years**

(21) Appl. No.: **29/855,295**

(22) Filed: **Sep. 30, 2022**

(51) **LOC (14) Cl.** **08-08**

(52) **U.S. Cl.**

USPC **D8/382**; D25/199

(58) **Field of Classification Search**

USPC D8/387, 397, 367, 382, 21, 354, 349,

D8/373, 394, 395, 45; D24/133;

D12/162, 223, 345; D25/133, 124, 68,

D25/199; D23/259, 262

CPC .. E01C 11/14; E01C 19/504; E04B 2005/324;

E04B 1/483

(57) **CLAIM**

The ornamental design for a joint former connector as shown and described.

DESCRIPTION

FIG. 1 is a top perspective view of a joint former connector of my new design.

FIG. 2 is a bottom perspective view of the joint former connector of FIG. 1.

FIG. 3 is a right side view of the joint former connector of FIG. 1.

FIG. 4 is a left side view of the joint former connector of FIG. 1.

FIG. 5 is top view of the joint former connector of FIG. 1.

FIG. 6 is bottom view of the joint former connector of FIG. 1.

FIG. 7 is a front view of the joint former connector of FIG. 1; and,

FIG. 8 is a rear view of the joint former connector of FIG. 1.

The broken lines in the drawings depict portions of the joint former connector that form no part of the claimed design.

1 Claim, 8 Drawing Sheets
